FOREIGN PATENT DOCUMENTS

TW D159216 S 3/2014
TW D160371 S 5/2014*Primary Examiner* — Marissa J Cash*Assistant Examiner* — Rebecca Tsehaye(57) **CLAIM**

I claim the ornamental design for a nicotine inhaler, as shown and described.

DESCRIPTION

FIG. 1 is a top perspective view of my new design for a nicotine inhaler;

FIG. 2 is a top view thereof;

FIG. 3 is a right side view thereof;

FIG. 4 is a bottom view thereof;

FIG. 5 is a left side view thereof;

FIG. 6 is a front view thereof; and,

FIG. 7 is a rear view thereof.

The broken lines in the drawings depict portions of the nicotine inhaler that form no part of the claimed design.
